Patented Oct. 3, 1916.

2 SHEETS—SHEET 2.

UNITED STATES PATENT OFFICE.

CHARLES H. PERKINS, OF LACONIA, NEW HAMPSHIRE, ASSIGNOR TO CRANE MANUFACTURING COMPANY, OF LAKEPORT, NEW HAMPSHIRE, A CORPORATION OF NEW HAMPSHIRE.

STOP-MOTION FOR KNITTING-MACHINES.

1,200,018.

Specification of Letters Patent.

Patented Oct. 3, 1916.

Application filed April 7, 1916. Serial No. 89,591.

To all whom it may concern:

Be it known that I, CHARLES H. PERKINS, of Lakeport, in the city of Laconia, county of Belknap, and State of New Hampshire, have invented a certain new and Improved 5 Stop-Motion for Knitting-Machines, of which the following is a specification.

The stop motion constituting the present invention is intended to automatically stop 10 the machine in case a needle is bent, or a bunch of yarn is fed to the needles, or in any other contingency which interferes with the proper action of the yarn feed.

The improvement is illustrated in the accompanying drawings in which—

Figure 1, is a plan view of a portion of a knitting machine equipped with the improvement. Fig. 2, is a detail view of a portion of the stop mechanism. Fig. 3, is a 20 vertical section in the plane indicated by the line 3—3, in Fig. 1. Fig. 4, is a vertical section in the plane indicated by the line 4—4, in Fig. 1. Fig. 5, is a vertical section in the plane indicated by the line 5—5 in Fig. 1. 25 Fig. 6, is a detail view of a portion of the stop mechanism.

The improved stop motion is shown in the drawings as applied to a circular multiple feed ribbing knitting machine having two 30 sets of independent spring bearded needles, and in which the needles and their carriers rotate, their actuating devices and the feeds being mounted on fixed supports. The knitting machine illustrated is of the same general 35 character as that set forth in United States Letters Patent No. 880,013, granted February 25, 1908, to John S. Crane. The accompanying drawings illustrate only a portion of the knitting machine, two yarn feeds being shown.

Each of the yarn feeds comprises a rotating feed wheel A, which may be of the character illustrated in said Patent No. 880,013, or of the character illustrated either in Fig. 45 18, or in Fig. 20, of United States Letters Patent No. 1,027,034, granted May 21, 1912, to Crane Manufacturing Company, assignee of John S. Crane. Each yarn feed wheel A, is mounted to rotate upon a movable support 50 consisting of a bracket B, which is mounted to swing upon the bed plate C, of the machine, its axis being indicated at a. Each yarn feed supporting bracket B, is maintained in the normal working position 55 by means of a spring D, which holds it

against a fixed stop b. This spring suffices to maintain the yarn feed in working position but yields readily in case of need to permit the yarn feed support to move. Above each rotating feed wheel A, is a stationary plate E, rigidly secured to the support B, in a manner similar to that shown in Fig. 20, of said Patent No. 1,027,034. In case a needle is bent, or a bunch of yarn is fed to one of the feed wheels, the corresponding support B, swings on its axis in the direction indicated by the arrow c, in Fig. 1, against the tension of the spring D. This movement of the feed wheel carrying support is utilized to effect the automatic 70 stoppage of the machine.

As shown in Fig. 4, each plate E, has a vertically extending pin d. Alongside and in the path of this pin d, is the outer end of a transmitter consisting of a lever F, which 75 is centrally pivoted at e, to the stationary plate G of the machine which carries the dial cams. The inner end of each transmitter F, extends over the top of a loose stop ring U, which is similar to the stop ring 80 shown at U, in said Patent No. 880,013. This stop ring is concentric with the central axis of the knitting machine and it is mounted to have a limited rotary movement on the fixed cap plate H. As illustrated it is 85 loosely guided by fixed guides f. This stop ring extends throughout nearly an entire circle and sufficiently far to coöperate with all of the yarn feeds. This stop ring U, carries as many upwardly extending and adjustably secured shoulders I, as there are 90 yarn feeds, one of said shoulders being alongside and in the plane of the inner end of one of the transmitters F. Accordingly, whenever one of the yarn feed supports 95 swings on its axis a, due to a broken needle, or a bunch of yarn or any incident which causes such swinging, the corresponding transmitter F, is swung on its pivot and the stop ring U, is turned in the direction of the arrow g, shown in Fig. 1. This rotary movement of the stop ring G, is utilized to automatically stop the machine through appropriate 100 stopping mechanism and intermediate coöoperating connections.

As illustrated in the accompanying drawings, the stopping mechanism which effects the stoppage of the machine is similar to that shown in said Patent No. 880,013, and for convenience of comparison similar ref. 110

erence characters are here employed. The machine selected for illustration is driven from a belt pulley 74, by a friction clutch of well known character which comprises a 5 loose sliding cam 75, the clutch being such that when the cam is farthest from the pulley the machine is driven, and when nearest the pulley the machine is stopped. This sliding cam is moved out and in by a bell 10 crank shipper lever 76, being moved out by a spring 77, to stop the machine, and being moved in to start it again by the handle 78. This shipper lever 76, is caught and held in its inner position by a catch 15 lever 79, which is moved automatically to catch the lever by a spring 80. The free end of the upper horizontal arm of this catch lever 79, stands normally (that is when the machine is running) just below a 20 knock-off pin 81, which slides vertically in a guide bracket 82, secured to the bed plate C. This knock-off pin is forced downward quickly by a spring 83, and is lifted by a hand knob 84. It is held uplifted by a 25 latch J, which enters an annular recess h, therein. This latch J, is carried by an upwardly extending crank arm K, on a rock shaft L, which is journaled in the bracket 82, as illustrated in Fig. 3. This rock shaft 30 L, is maintained in the position to uphold the knock-off pin 81, by means of a spring i. At its inner end this rock shaft has a downwardly extending crank arm M, having a toe j, at its lower end. This crank 35 arm M, is adjustable on the rock shaft. This toe is adjacent the outer downturned end of a hammer N, which is pivotally connected at its middle at k, to the fixed ring G. The inner end of this hammer N, is forked 40 (see Fig. 1) to straddle a vertically extending pin O, carried by the stop ring U. When, therefore, the stop ring U, is turned in the direction of the arrow g (Fig. 1) the hammer N, is turned so as to rock the rock 45 shaft L, in opposition to the spring i, thereby withdrawing the latch J, from the annular recess h, of the knock-off pin 81. Thereupon, the knock-off pin is moved quickly downward by its spring 83, encountering the outer end of the horizontal arm of 50 the catch lever 79, and swinging said lever. The swinging of the catch lever 79, releases the shipper lever 76. Thereupon the spring 77, swings the shipper lever 76, so as to slide 55 the cam 75, to its idle position thereby stopping the machine. To set the machine again going, after the attendant has cured the defect, the support B, carrying the feed wheel at the place where the defect occurred, 60 is restored to its normal working position by the spring D. Thereupon the attendant lifts the knock-off pin 81, by means of the knob 84, until the latch J, springs into the recess h, under the action of the spring i. 65 This swing of the rock shaft L, into

normal working position acting through the crank arm M, and the hammer N, restores the stop ring U, and the affected transmitter F, to normal working position. The attendant then moves the shipper handle 78, 70 to set the machine going, and the spring 80, restores the catch lever 79, to the position where it catches and holds the shipper lever in working position.

The rock shaft L, has a thumb piece Q, by 75 means of which said shaft may be rocked and the machine stopped at the will of the attendant.

The vertical pin, shown in Figs. 3 and 6, as carried by the crank arm M, is the 80 same in function as pin 86, shown in Fig. 4, in said Patent No. 880,013, and described therein beginning at line 60, page 2. Its purpose is to rock the shaft L, and to stop the machine in case of an imperfection in 85 the fabric.

I claim—

1. A knitting machine having, in combination, a central cap plate, a plurality of 90 yarn feeds, each comprising a swinging supporting bracket and a feed wheel mounted thereon; a spring normally maintaining each yarn feed in working position; a pin carried by each bracket and extending upwardly above each feed wheel; a movable stop-ring on the cap plate coöperating with all of the yarn feeds, and having a shoulder for each yarn feed; a centrally pivoted transmitter on the cap plate for each yarn feed extending at its outer end into the path 95 of one of said pins and at its inner end alongside one of said shoulders; and shipping mechanism operatively connected with and controlled by said stop-ring.

2. A knitting machine having, in combination, a central cap plate, a plurality of 105 yarn feeds, each comprising a movable support and a feed wheel mounted thereon, a spring normally maintaining each yarn feed 110 in working position; a pin carried by each support and extending upwardly above each feed wheel; a movable stop-ring on the cap plate coöperating with all of the yarn feeds, and having a shoulder for each yarn feed; a transmitter on the cap plate for each 115 yarn feed extending into the path of one of said pins and alongside one of said shoulders; and shipping mechanism operatively connected with and controlled by said stop-ring.

3. A knitting machine having, in combination, a central cap plate, a plurality of 120 movable yarn feed supports; a spring normally maintaining each yarn feed support in working position; a movable stop-ring on the cap plate coöperating with all of the yarn feeds, and having a shoulder for each yarn feed; a transmitter on the cap plate for each 125 yarn feed extending at its outer end into the path of a part of one of said yarn feeds 130

and at its inner end alongside one of said shoulders; and a shipping mechanism operatively connected with and controlled by said stop-ring.

5 4. A knitting machine stop motion having, in combination, a knock-off pin; a rock shaft having a crank arm with a projecting latch which engages said pin; a spring

which normally maintains said latch in such engagement; and a crank handle on said 10 rock shaft by means of which the latch can be released from the pin at will.

In witness whereof, I have hereunto signed my name.

CHARLES H. PERKINS.
